ATTORNEY

UNITED STATES PATENT OFFICE.

WESLEY H. HARPER, OF BERLINSVILLE, PENNSYLVANIA.

BUSH-HAMMER.

SPECIFICATION forming part of Letters Patent No. 314,291, dated March 24, 1885.

Application filed June 18, 1884. (No model.)

To all whom it may concern:

Be it known that I, WESLEY H. HARPER, a citizen of the United States, residing at Berlinsville, in the county of Northampton and 5 State of Pennsylvania, have invented certain new and useful Improvements in Bush-Hammers, of which the following is a specification, reference being had therein to the accompanying drawings.

10 My invention relates to certain improvements in bush-hammers, and is designed to allow the easy placing and removal of the "cuts," to hold them firmly in place, and provide a means whereby the least waste of the material of the cuts possible is accomplished.

15 In describing the device, reference will be had to the accompanying drawings, in which Figure 1 represents a section longitudinally through the hammer; Fig. 2, a plan view of 20 an extra "gib," and Fig. 3 a plan and edge view of a "filler."

A designates the body of the hammer, constructed preferably of steel, and constitutes what is technically known as the "pole" of 25 the hammer. Each end of the said pole is slotted for the reception of the ends of the cuts B, and also at each end, on one side, is recessed for the reception of the movable jaws C. These jaws are so constructed as to project over the ends of the cuts coincident with the fixed projecting jaws D on the pole. The bearing end of the jaws is shouldered and the continuation toward the other end gradually thickened, so as to make the thinnest portion 30 of the jaw at the beginning of the shoulder. This gives the shouldered portion considerable play, forming a strong clamping-lever of the said jaw, the thickened end being the fulcrum, the bolt the power, and the shoulder the bearing portion. The jaw being thickened toward the one end, gives it a greater play than though it were of the same size. Passing 35 through the jaw and into the body of the pole is a bolt, E, having the portion directly in the jaw beveled, as shown at F. This allows the quick disengagement of the jaw and the cuts when the bolt is loosened but slightly, as a small withdrawal of the said bolt, by reason of the bevel, quickly diminishes the relative 40 diameter of the bearing portion F, and so allows considerable lateral and, of the shouldered portion of the jaw, vertical play. Both

the fixed and the movable jaw are provided with a slot, G, in which is adapted to fit a lug, H, on the filler I, to prevent it slipping from 55 its place in the hammer, its purpose being to rest between the cuts and the jaws between which they set, and aid materially in keeping the said cuts firmly clamped in place.

Centrally in the slots in which the cuts rest 60 is a lug or key, L, which is preferably beveled, and is for the purpose of easily disengaging or relieving the cuts when the jaw is loosened, and also keeping them firmly in place and preventing them moving when clamped. 65 An extra piece or gib is provided to allow the use of the cuts till they are nearly worn away. This piece is shown at K, and is provided with a beveled slot, M, to allow it to engage with the key L, and is also provided with a similar key corresponding in position. In Fig. 1, one end is shown with the gib in place and the other end with it removed, thus showing its use with short or worn cuts. Through the edge of the hammer or pole is an eye, N, for 70 the reception of the handle. The usual mode is to have the eye pass through the pole parallel to the cut-holding slots; but by passing through the edge or at right angles to the said slots any side strain that may be exerted on the 75 cuts is withstood by the jaws and not by the force of the clamping, as is the case in the ordinary pole.

In large bush-hammers the jaws are held by more than one bolt.

Having described the device, what I claim is—

1. A bush-hammer having its pole provided with movable jaws, each of the said jaws having at one end a shoulder which bears on the 90 cuts or picks, and being gradually thickened from the shoulder toward the other end, substantially as and for the purpose specified.

2. A bush-hammer having its pole provided with movable jaws, each of the said jaws having at one end a shoulder which bears on the 95 cuts or picks, and being gradually thickened from the shoulder toward the other end, the said thickened portion having passed through it the beveled portion of the securing and 100 clamping bolt or bolts, substantially as and for the purpose specified.

3. In combination with a bush-hammer having a pole provided with clamping-jaws, a gib

having a recess on one side for receiving the lug or key on pole, and provided on its other side with a lug or key, the said gib resting behind the butts of the cuts or picks, substantially as and for the purpose set forth.

4. In combination with the jaws of a bush-hammer pole, the said jaws being slotted on their bearing-surfaces, a filler resting between the jaws and the cuts, and provided with a lug on its surface to engage in the slot in the jaw, which lug prevents the filler from slipping, substantially as and for the purpose set forth.

5. A bush-hammer having a pole provided with movable shouldered jaws retained in place

by bolts, with the portions passing through the jaws beveled, a removable gib provided with a lug and a recess, and a filler provided with a lug fitting in a slot in the jaws, the said pole having a lug at the rear of the cut-retaining recess, and being provided centrally with an eye for the handle, the entire device operating substantially as and for the purpose set forth.

In testimony whereof I affix my signature in presence of two witnesses.

WESLEY H. HARPER.
